J. H. RIDINGS.
EXTENSION LADDER.
FILED JULY 21, 1920.

UNITED STATES PATENT OFFICE.

JOHN HENRY RIDINGS, OF COAL CITY, ILLINOIS.

EXTENSION LADDER.

Application filed July 21, 1920. Serial No. 398,017.

To all whom it may concern:

Be it known that I, JOHN HENRY RIDINGS, a citizen of the United States, residing at Coal City, in the county of Grundy and 5 State of Illinois, have invented certain new and useful Improvements in Extension Ladders, of which the following is a specification.

My invention relates to improvements in 10 extension ladders, and more particularly to the construction, mounting and general arrangement of the round engaging members or hooks pivotally carried by the extension ladder section and adapted to swing in a 15 plane at right angles to the longitudinal plane of the rounds of the stationary ladder section.

The primary object of the invention is to 20 provide a generally improved mounting for the round engaging member or hook for use in connection with extension ladders, which will be exceedingly simple in construction, cheap of manufacture, and efficient in use.

25 With the above mentioned and other ends in view, the invention consists in the novel construction, arrangement, and combination of parts, hereinafter described, illustrated in one of its embodiments in the accompanying drawings, and particularly pointed out in the appended claim.

Referring to the drawings, forming a part 30 of this specification, Figure 1 is a perspective view of the improved extension ladder with the round engaging member in detached position preparatory to extending or elevating the extension ladder section.

Fig. 2, a side elevation of one of the round 35 engaging members or hooks detached.

40 Fig. 3, an enlarged rear elevation of the same, the bearings and attaching bracket elements being shown in section and disassembled.

Fig. 4, a fragmentary longitudinal sectional view of the adjacent ladder section 45 and illustrating the open or detached positions of the round engaging members as in moving or adjusting the movable or extension ladder section relatively to the lower or stationary ladder section.

50 Fig. 5, a similar view, illustrating the relative position of the parts in lowering the extension ladder section, and particularly showing the hooks closed by the runner closure member as it moves or passes

over an adjacent round of the stationary ladder section.

Fig. 6, a similar view, illustrating the round engaging position of the hooks.

Similar numerals of reference designate 60 like parts thruout all the figures of the drawings.

The improved ladder comprises a relatively fixed or stationary ladder section 1, and a relatively movable or extension ladder 65 section 2.

The ladder sections 1 and 2 comprise the usual side members provided with the usual rounds 1^a and 2^a, respectively.

The side members of the extension section 70 2, are mounted within the side bars of the stationary section 1 in the usual manner, and are guided at their upper ends by means of guide members or clips 3.

The extension section 2 may be extended 75 and retracted in any suitable and convenient manner, as for example,—by means of a cable 4 connected to one of the rounds of the extension section and extending upwardly and over a pulley 5 of the stationary 80 section and returning downwardly within easy reach of an operator from the base of the stationary section.

Referring now to the improved round engaging members or hooks and the improved 85 method of mounting the same to which this invention particularly relates, it will be seen that the round engaging hooks or members are arranged in pairs on the inner sides of 90 the side bars of the movable or extension section, and in view of the fact that such hooks or members are duplicates of each other and operate simultaneously a detailed description of one will describe the other.

The round engaging member comprises a 95 main body portion 6, terminating at one end in a bearing head 6^a, having an opening to receive and take over the bearing head 7^a of a bracket member 7, detachably secured to the inner side of the adjacent side 100 bar of the ladder by means of attaching screws 7^b. As a means of removably securing the bearing head 6^a, of the pivoted round engaging member, a bolt 7^c is removably mounted in the bearing head 7^a of the 105 bracket 7, and is connected at its inner end by means of a nut 7^d, a washer 7^e being mounted beneath the nut 7^d to retain the hook engaging member in position.

The round engaging members 6, swing 110

freely on the bearing heads 7^a of the bracket 7, and depend therefrom.

Each round engaging member is provided at its lower end with spaced projections 5 forming round engaging stop and hook members 6^b and 6^c, spaced apart forming a guideway adapted to receive and contain one of the rounds 1^a of the stationary ladder section 1, the rear inclined arm of the round 10 engaging member being inclined to successively pass over and be reciprocated by the rounds of the stationary ladder section when elevated as indicated in Fig. 4 of the drawings.

As a means of initially closing the hook member 6^c when it is desired to elevate and detach the latter from the rounds of the lower section 1 when in engaged position as shown in Fig. 6, and when the hook is raised 20 upwardly by the elevation of the extension section 2 to a position substantially as shown in Fig. 4 and whereby upon the return of the extension section as illustrated substantially in Fig. 5, the hook 6^c will 25 successively be closed as the upper or extension section 2 is moved downwardly, the curved stop member 6^b is provided with a hook closure runner member 8 pivotally connected by means of a pivot pin 8^a extending thru side bearing lugs 8^b of the runner member, said runner member being curved as shown and having its tip 8^c adapted to engage and close the hook member 6^c, so that when the extension section is lowered from 35 the position shown in Fig. 4 toward the position shown in Fig. 5 the tip of the runner member 8 will engage with the adjacent lower round of the stationary ladder section and swing the round engaging member outwardly to pass over the round, as 40 illustrated in Fig. 5.

When the extension ladder section 2 is moved upwardly from engagement with one round of the stationary ladder section to another or successively higher round, the round engaging members will be rocked on pivots and successively pass over the rounds as will be obvious upon reference to Fig. 4.

Should it be desired to engage one of the 50 rounds of the lower or stationary section to secure the upper or extension section in position, said extension section 2 may be given an initial elevating movement sufficient to allow the rear side of the round

engaging member to ride over the adjacent 55 round and the tip of the hook member 6^c to clear the round of the stationary member or ladder section, whereupon a slight retracting movement of the extension ladder section will cause the hook 6^c to engage with the rounds as shown in Fig. 6 of the drawings.

It will be seen that the stop and hook members 6^b and 6^c limit and confine the movements of the round engaging members, 65 and that the hook closure runner members 8 act to automatically close the hooks 6^c and prevent their engaging with the successive rounds of the stationary sections as the upper section 2 is returned over the lower section, such members forming runner members so that the same will ride over the successive rounds transmitting a reciprocatory movement to the round engaging members as a whole until the desired adjusted position of the extension section is reached, 70 whereupon the same may be moved to cause the hook members 6^c to engage with the rounds of the stationary ladder section in the manner hereinbefore described.

Having thus described one of the embodiments of my invention, without having attempted to set forth all the forms in which it may be made or all the modes of its use, what I claim and desire to secure by Letters Patent, is,—

In a mounting for extension ladder round engaging hooks, an attaching bracket adapted to be secured to the inner side of one of the rails of the adjacent extension ladder section and provided with a bearing head having a bolt receiving opening extending axially therethrough said opening being enlarged on the rail-engaging side of said attaching bracket, a bolt extending through 95 said opening and having a head seated in said enlarged portion of the opening and covered by said attaching bracket when the latter is mounted, a round engaging member having a bearing head pivoted on said bearing head of said bracket, and a fastening element detachably secured to the inner end of said bolt and bearing against said bearing head of said round engaging member.

In testimony whereof I have affixed my 105 signature.

JOHN HENRY RIDINGS.
